UNITED STATES PATENT OFFICE.

ANDREW L. RIKER, OF FAIRFIELD, CONNECTICUT.

VENTILATOR.

Application filed October 1, 1925. Serial No. 59,890.

This invention relates to a ventilator, useful for many purposes, but more especially adapted for use as a closure for transoms, doorways, windows, panels, or the like.

5 An object of the invention is to provide a ventilator of the general nature of those described and illustrated in my Patents, No. 1,519,553, granted December 16, 1924, and No. 1,529,037, granted March 10, 1925, and 10 No. 1,666,218, granted April 17, 1928, and presenting advantageous characteristics and features of construction which are improvements over the disclosures of said patents.

A further and more specific object is to 15 provide a ventilator consisting of a frame having a plurality of louvers pivoted therein to turn on their axes and preferably so proportioned and arranged that when swung in one direction they will completely close the 20 space within the frame and when swung in the other direction will leave passage ways between the respective louvers without opening a direct line of vision through the frame, and to equip the ventilator with improved 25 operating mechanism for swinging the louvers to open and closed position, which operating mechanism will be efficient and dependable, and of simple and economical construction.

30 A still further object is to provide a ventilator consisting of a frame and a plurality of louvers pivoted therein as stated, wherein the pivoted louvers will themselves cooperate with certain of the frame members to close 35 end spaces in the frame when the louvers are swung to closed position, precluding the necessity for providing in the ventilator special fixed louvers as heretofore utilized to close said end spaces.

40 Another object is to provide a ventilator consisting of a frame and a plurality of louvers pivotally mounted therein, the frame being composed of flanged plates, certain of which plates have flanges extending inwardly 45 of the frame, and certain of which plates are of peculiar construction and have flanges extending outwardly of the frame, the whole frame being constructed to accomplish advantageous results desired in a ventilator of the present general character, certain of which results are: (1) interlapping of the 50 ends of the louvers with the inwardly extending flanges of plates adjacent the louver ends; (2) closure of the end spaces in the frame 55 and parallel with the louvers when said louvers are closed, by direct engagement of outer-

most louvers with plates of the frame adjacent said end spaces and having the peculiar construction to be fully described; (3) an arrangement of the plates of the frame relatively to each other whereby the plates can be more easily welded or otherwise secured together to produce the frame than could individual plates of a frame wherein all of the plates had inwardly extending flanges; and 60 (4) a construction and arrangement of outer plates (those which are of the peculiar shape to be described) adapted to render the incorporation of the finished ventilator in a structure a simple task; that is to say, a construction and arrangement of plates better suited 65 to the insertion of a screw or screws in the ventilator and in a structure to hold the ventilator.

And yet another object is to provide in the 70 ventilator an operating mechanism which, while of very simple and economical construction, will be designed to provide for manipulation of the louvers to closed and to open position by the expenditure of but a 75 minimum of manual effort.

With the above objects in view, as well as others which will appear as the specification proceeds, the invention comprises the construction, arrangement and combination of 80 parts as now to be fully described and as hereinafter to be specifically claimed, it being understood that the disclosure herein is merely illustrative and meant to in no way limit the spirit of the invention, changes in 85 details of construction and arrangement of parts being permissible so long as within the scope of the appended claims.

In the accompanying drawing forming a 90 part of this specification,

Fig. 1 is an elevational view of the novel 95 ventilator, showing the louvers in open position;

Fig. 2 is an enlarged sectional view, taken on line 2—2 in Fig. 1, showing the ventilator 100 as when incorporated in a transom, doorway, window, panel, or the like, the louvers being in open position;

Fig. 3 is a view corresponding with the showing of Fig. 2, with louvers in closed position and transom, doorway, window, panel, or the like, omitted;

Fig. 4 is a detail perspective view disclosing the manner of securing the top member or plate of the frame with each side member 110 thereof;

Fig. 5 is a detail perspective view disclos-

ing the manner of securing the bottom member or plate of the frame with each side member thereof;

Fig. 6 is an enlarged fragmentary sectional view taken on line 6—6 in Fig. 1;

Fig. 7 is an enlarged fragmentary sectional view taken on line 7—7 in Fig. 1;

Fig. 8 is a detail sectional view as on line 8—8 in Fig. 3; and

10 Fig. 9 is an elevational view corresponding with the showing of Fig. 8, the frame member or plate and the louver ear being omitted.

The ventilator of this invention is constituted by a frame of rectangular configuration, 15 louvers pivoted therein, and mechanism for swinging the louvers on their pivots to open and close the space within the frame.

The frame, as shown, is composed of sheet metal, it consisting of a top member 10, a 20 bottom member 11, and side members, denoted 12 and 13, respectively. All of the members of the frame are flanged plates, the top and bottom members having flanges, denoted 14 and 15, respectively, extending outwardly for the full lengths of said members from their opposite edges, and the side members having flanges 16 extending inwardly, 25 preferably at right-angles, for the full lengths of said members from their opposite edges.

30 A manner in which the members 10, 11, 12 and 13 may be joined is best shown in Figs. 4 and 5, wherein an end portion of a member, such as member 10 in Fig. 4, and 11 in Fig. 5, and its flanges, 14 in Fig. 4, and 15 in Fig. 5, are drawn or offset inwardly, as denoted at 35 17, and the flanges 16 of the members 12 and 13, respectively, fit snugly over the drawn in or offset portions 17 to align with the flanges 14 and 15, respectively. The connection between the members 10 and 12, 13, and between the members 11 and 12, 13, may be made in 40 any suitable manner, as, for example by welding the plates to each other at the four corners of the frame. In the finished frame, all 45 of the flanges 14, 15 and 16 either align, or are parallel. See Figs. 2, 3, 4 and 5. The body portions of the plates 12 and 13 may be flat as disclosed. The body portions of the plates 10 and 11 are of the peculiar construction 50 presently to be described. As will be very clear from Figs. 4 and 5, the outer edges, denoted 18 and 19, respectively, of the flanges 14 and 15 preferably terminate flush with the ends, denoted 20, of the flanges 16, and with the 55 ends, denoted 21 and 22, respectively, of the plates 12 and 13, for the sake of producing a compact and wholly sightly ventilator.

The louvers are preferably composed of sheet metal. As shown, they are mounted in 60 the frame to be parallel with the members 10 and 11 and perpendicular to the members 12 and 13, and all of the louvers are pivoted in the frame and are of V shape, although they might be of different shape. Said louvers 65 are mounted in the members 12 and 13 in the

manner best shown in Figs. 2, 3, 6, 7 and 8. That is to say, each louver 23 has an ear 24 upon its arm 25 pivoted upon the member 12, and an ear 26 upon this same arm pivoted upon the member 13, the arm 27 of each louver 70 being free of ears. The ears 24 and 26 preferably extend at right-angles in the same direction from the arm 25 of the louvers 23, and, as shown, the ears 24 are situated within the space between the arms 25 and 27, while 75 each ear 26 has an extension 28 in the plane of the ear 26 but projecting obliquely therefrom and terminating slightly beyond the adjacent arm 27. See Figs. 2 and 3. Each of the ears 24 is provided with a hole rotatably receiving a drawn portion 29 of the metal of the member or plate 12 of the frame, and each of the ears 26 is drawn as at 30 to rotatably enter an annular flange 31 consisting of upwardly or inwardly drawn metal of the 85 member or plate 13 of the frame, the pivotal points for the louvers being arranged adjacent the opposite ends of the arms 25 thereof not far from the midwidths of said arms.

Numeral 32 denotes an operating bar for 90 manipulating the louvers. The operating bar is arranged beneath the extensions 28 of the ears 26 to slide upon the plate 13 of the frame and each of the extensions 28 has metal drawn therefrom and rotatably entering holes 33 95 at uniform distances apart in the operating bar.

The mechanism for moving the operating bar longitudinally to turn the louvers on their pivots consists of a manipulating lever 34 100 having an opening 35 in its inner end portion adapted to fit upon an end annular flange 31, as indicated more clearly in Fig. 8, and also having an opening 36 adjacent the opening 35 adapted to rotatably and snugly receive 105 the preferably circular end 37 of the operating bar 32. Adjacent the opening 36 (at the side thereof having the operating bar), the metal of the manipulating lever 34 is offset, as indicated at 38, in a direction away from 110 the frame member or plate 13, to clear the operating bar. See Figs. 8 and 9. Evidently, the metal at 38 could be cut away, but then the cross-sectional area of the manipulating lever would be considerably weakened. An 115 intermediate portion, denoted 39, of the manipulating lever is movable in an elongated slot 40 in a flange 16 adjacent the frame member or plate 13 (see Fig. 1), and adjacent the slot (just beyond said flange 16), the metal 120 of the manipulating lever has a quarter-circle twist 41 providing a finger piece 42 which is preferably perpendicular to the body of the member or plate 13, whereby the manipulating lever can be readily oscillated to open 125 and close the louvers, as will be understood.

It will be evident that the manipulating lever works about said end annular flange 31 as a fulcrum of a lever of the second class, the rotatable engagement of said manipu- 130

lating lever with the operating bar being the location where the work (the swinging of the louvers on their pivots) is accomplished, and that the power (labor) required to throw the 5 louvers on their pivots depends upon the relation of the short arm (length of the manipulating lever between the openings 35 and 36) of the lever, to the long arm (length of the manipulating lever opposite the opening 35 10 and beyond the opening 36) thereof. That is to say, the outer portion of the manipulating lever can bear a relation to the inner portion thereof requiring the expenditure of but a minimum of manual effort to throw the 15 louvers toward open or closed position. It will also be evident that the component parts of the operating mechanism and of the ventilator are so associated and related that each part is fixedly situated in the ventilator. The 20 inner end portion of the manipulating lever is located between an ear 26, including its extension 28, and the member or plate 13. The outer portion of said lever is located by the slot 40. The rounded end of the operating 25 bar is located by the manipulating lever and the offset portion 38 thereof, being located between said offset portion and the plate 13, and the whole length of said operating bar is located by the extensions 28 of the ears 26 of 30 the louvers.

The drawing of the metal of the member or plate 13 of the frame upwardly or inwardly to form the annular flanges 31, provides a space 43 between the extensions 28 of the ears 35 26 of the louvers and said member or plate 13 to afford clearance for the longitudinal sliding movements of the operating bar upon the member or plate 13. See Fig. 7.

In Figs. 1 and 2 the louvers are shown in 40 wide open position. In said figures, all of the arms 25 are parallel and spaced at equal distances apart, as are all the arms 27. In Fig. 3 the louvers are shown in closed position. Here the free or outer edge portion or 45 margin of each arm 27 engages for its full length the attached or inner edge portion or margin of the arm 27 of the louver next adjacent it (below it as disclosed in the drawing), to effect a positive closing between all of the louvers. Special provision must be made to 50 close the spaces of the ventilator between outermost louvers and the frame members or plates 10 and 11, respectively. Fig. 3 clearly discloses a manner in which these spaces are 55 closed without the employment of fixed louvers. As there shown, the body of the frame member or plate 10 includes a surface 44 extending the full length of said member or plate 10, which is approximately parallel 60 with the flanges 16 and about in the plane of the arms 27 of the louvers when closed, so that the full length of the attached or inner edge portion or margin of the adjacent outermost arm 27 can be engaged by said surface 44 65 when the louvers are closed, in about the man-

ner that the inner edge portion or margin of each other louver is engaged by the outer edge portion of an adjacent louver. Similarly, the body of the frame member or plate 11 includes a surface 45 extending the length of 70 said member or plate 11, which is also approximately parallel with the flanges 16 and about in the plane of the arms 27 when closed, so that the full length of the free or outer edge portion or margin of the adjacent outermost 75 arm 27 can engage said surface 45 for its full length.

It should be remarked that the end portion of the member or plate 11 adjacent the member or plate 13 is cut away to clear the manipulating lever (see Fig. 3), although the construction could be such that said member or plate 11 and the manipulating lever 34 are 80 always spaced apart, as will be apparent.

In addition to providing the surfaces 44 and 85 45, the members or plates 10 and 11, respectively, should provide surfaces adapted to readily receive screws, or other attaching means whereby the ventilator can be incorporated in a structure such as indicated at A 90 in Fig. 2. As more clearly disclosed in Figs. 2, 3, 4 and 5, the surface 44 of the plate 10 merges in a surface 46 which is between the surface 44 and a flange 14, and the surface 45 of the plate 11 merges in a surface 47 between 95 the surface 45 and a flange 15. These surfaces have holes to receive screws B, or other attaching means, and are desirably obliquely disposed in such manner as to render easy the insertion of the screws in the plates 10 and 11 100 of the ventilator and in a structure such as represented at A. The remaining portions of the bodies of the members or plates 10 and 11 can be of any suitable structure, so long as there is not interference between said bodies 105 and the louvers.

In assembling the louvers with the frame 12, I desirably utilize rivets 48 as suggested in Fig. 6, to first secure the ears 24 to said member 12. I may also utilize rivets to 110 secure the ears 26 to the frame member 13.

The ventilator as illustrated and described is of very simple construction. The frame consists of but four sheet metal plates rigidly secured to each other. Each louver with its ears consists of a single piece of sheet metal bent to V shape and mounted in the frame. The operating mechanism consists of an operating bar and a manipulating lever associated in novel and improved manner with a frame member and with the operating bar. The elements going to make the ventilator are relatively few and the positions of all of the elements are positively insured, no liability whatsoever existing that any element 115 can become dislocated or impaired. Hence, the ventilator is durable, reliable and efficient for a long period of time.

To incorporate the ventilator in its position of use, all that is necessary is to fit the 120 125 130

frame into an opening, the flanges of the frame members or plates 12 and 13 serving the purpose of inclosing the ends of all of the louvers, and the surfaces 44 and 45 of the frame members or plates 10 and 11, respectively, overlapping with outermost louvers when in closed position to preserve the advantageous features of the ventilator.

By reference to Figs. 2 and 3, it will be seen that I have so constructed the body portion of the frame member or plate 11 as to insure that it will have no horizontal surfaces or cavities to serve as receptacles for dirt, dust, etc., and I have so arranged said body portion that it can be readily dusted or cleaned.

Frame members or plates constructed after the fashion of members or plates 10, 11 render the individual frame members more easily connectable, especially by welding, than do plates of a frame all of which are like the plates 12, 13. Likewise, frame members or plates having surfaces such as 46, 47, adapted to readily receive screws B, render the incorporation of the finished ventilator in a structure, such as A, a simple task, much easier to accomplish than when all of the members or plates of a ventilator are like the plates 12, 13.

Having thus fully described the invention, what I claim as new and desire to secure by Letters Patent is:

1. As an article of manufacture, a device comprising a rectangular frame consisting of joined metallic channel pieces, opposite channel pieces having their marginal portions extending inwardly of the frame, opposite channel pieces having their marginal portions extending outwardly of the frame, the opposite end portions of one set of the said opposite channel pieces being fitted between the opposite end portions of the other set of said opposite channel pieces, and louvers pivotally mounted in the channel pieces having inwardly extending flanges and between the other channel pieces, said louvers being adapted to be swung to open position to allow passages through the frame and to closed position to close all of said passages, and the outer faces of adjacent flanges of the frame being flush with each other.

2. As an article of manufacture, a device comprising a rectangular frame consisting of joined metallic channel pieces, opposite channel pieces having their marginal portions extending inwardly of the frame, opposite channel pieces having their marginal

portions extending outwardly of the frame, the opposite end portions of one set of the said opposite channel pieces being fitted between the opposite end portions of the other set of said opposite channel pieces, and louvers pivotally mounted in the channel pieces having inwardly extending flanges and between the other channel pieces, said louvers being adapted to be swung to open position to allow passages through the frame and to closed position to close all of said passages, and the opposite end portions of the said channel pieces which fit between the said other channel pieces including flange offset portions.

3. In a device of the character described, a metallic plate having flanges, louvers having ears pivotally supported upon and spaced from said plate, an operating bar having spaced apart holes rotatably receiving portions of metal struck from said ears, said bar being arranged between said ears and said plate and between said flanges, and a manipulating lever mounted upon a louver axis, rotatably assembled with the operating bar, and arranged in a slot in a flange of said plate to extend beyond the confines of said device, said manipulating lever having its inner end portion situated between a louver ear and said plate and including an offset portion, and a part of said operating bar adjacent said lever being situated between said offset portion and plate.

4. In a device of the character described, spaced apart metallic plates having flanges, louvers having ears pivotally supported in the plates between the flanges, the ears being spaced from one of said plates, an operating bar having spaced apart holes rotatably receiving portions of metal struck from certain of the ears, said bar being arranged between said certain ears and the plate adjacent said ears, and a manipulating lever mounted upon a louver axis, rotatably assembled with the operating bar, and arranged in a slot of a flange of the plate adjacent said bar, to extend beyond the confines of said device, a portion of said lever being situated between a louver ear and said last mentioned plate, said lever including an offset portion, and a part of said operating bar adjacent said lever being situated between said offset portion and the last mentioned plate.

Signed at Bridgeport, in the county of Fairfield, and State of Connecticut, this 29th day of September, A. D. 1925.

ANDREW L. RIKER.
